CARRY BAG

George W. Poppe, Brooklyn, N. Y., assignor to
 Equitable Paper Bag Co. Inc., Brooklyn, N. Y.,
 a corporation of New York

Application December 20, 1938, Serial No. 246,795

2 Claims. (Cl. 229—68)

This invention relates to carry bags provided with tongues cut from the bag walls and is similar in some respects to the carry bag forming the subject matter of my application filed of even date herewith.

An object of the invention is to produce a bag of this character in which a tongue or tongues cut from the bag walls may coact with the closing flap of the bag in such a manner as to hold said flap in closed position.

A further object is the production of a bag in which one of the tongues cut from the bag walls may act as a reenforcing tongue and the other as a locking tongue in co-operation with the closing flap of the bag.

A further object is the production of a bag of this character which may be made on an ordinary bag machine and at substantially the same speed of an ordinary bag.

20 In the drawing, Figure 1 is a front elevation of the upper portion of the bag embodying the present invention;

Figure 2 is a perspective view of the bag shown in Figure 1 but with one of the wall tongues folded upwardly;

Figure 3 is a perspective view after one of the tongues has been folded upwardly and the closing flap folded down;

Figure 4 is a front elevation of the upper central portion of the bag after the closing flap has been folded down and the locking flap folded upwardly into locking position with the closing flap;

Figure 5 is a section on the line 5—5 of Figure 4; and

Figure 6 is a perspective view of a slightly modified form in which both of the tongues are folded upwardly into locking engagement with the closing flap of the bag.

40 The bag of the present invention may be formed by one of the methods disclosed in my Patent 1,798,168 and after the bag has been bottomed, the necessary punching may be accomplished by methods known to the art. As described in said patent, preliminary cuts are made in a web of paper which cuts form the side edges of the closing flap of the finished bag. The web is then folded into a tube which is subsequently severed into bag lengths.

50 Referring to Figure 1 of the present disclosure, such a bag includes a front wall 2 and a rear wall 4, Figures 3 and 5. In the present instance, the web is folded in such a manner as to produce a wide seam and the flap 6 which closes the mouth of the bag is a prolongation of the seam

wall. Paste lines indicated by the vertical dotted lines in Figure 1 are formed near the edges of the seam and in the center thereof. Within the seam and between the outer paste lines, tongues 8 and 10 are cut from the bag walls. The tongue 8 being cut from the front wall 2, contains one ply of paper while the tongue 10 cut from the seam wall contains two plies of paper, as clearly shown in Figures 5 and 6. A score line a—a is made across the bag and determines the line of fold when the flap 6 is folded down onto the front wall 2 of the bag. In addition to the tongues 8 and 10 in the bag walls, the flap of the bag is provided with a cut-out or recess 12 which recess may be the same width or somewhat narrower than the width of the tongues. The tongues are hinged along their upper portion at 14, the hinge line being shorter than the width of the tongues. The tongue 8 as shown in Figures 2, 3 and 5, may constitute a reenforcing tongue, which is folded upwardly as in Figure 2. The hinge line 14, of both tongues is spaced from the score line a—a, a distance substantially equal to the length of the tongues. Therefore, when the tongue 8 is folded upwardly against the wall 2, its edge opposite the hinge line will substantially coincide with the score line, or what amounts to the same thing, the line of fold of the flap 6. This flap may then be folded down and the tongue 10 passed through openings 16 in the bag walls and also folded upwardly into the recess 12, causing a locking action between the tongue and the flap 6. This locking action is brought about by reason of the shorter hinge line and by reason of the width of the cutout in relation to the width of the tongues. The upper corners of the tongue are also rounded at 18 and the corners of the recess 12 are also rounded at 20 so that when the tongue 10 is folded upwardly to the position shown in Figure 5, the tongue 10 and flap 6 are interlocked. The tongue 8 acts as a reenforcing member while the tongue 10 acts as a locking element and the rounded corners of the tongue openings tend to minimize the likelihood of a tear starting.

45 Both tongues may be passed through the openings 16 and folded back into the recess or cut-out 12 as shown in Figure 6.

It will be noticed that the line of fold or score line a—a, Figure 1, includes a small portion of 50 the bag wall 2 as indicated at 22, Figures 1 and 3. As shown in the latter figure, the tongue 8 is folded against the wall 2 between this wall and the upper turned-over portion 22. It is obvious of course that the tongue 8 may be turned up

between the turned-over portion 22 and the flap 6. A line of paste 24 may be applied across the seam adjacent the hinge line 14 as shown in Figure 1.

It is to be observed that the flap 6 may be of different lengths and that the line of fold of this flap may be at the base thereof.

What I claim is:

1. A carry bag having front and back walls and a closing flap at the mouth of the bag, a re-enforcing tongue and a locking tongue cut from the bag walls, said tongues hinged at their upper edges adapting them to be folded upwardly, a cut-out in the closing flap, said reenforcing tongue adapted to be folded upwardly prior to folding down of the flap, the locking tongue

adapted to be folded upwardly into said cut against the flap when the flap is folded down.

2. A carry bag having front and back walls and a closing flap at the mouth of the bag, a reenforcing tongue and a locking tongue cut from the bag walls, said tongues hinged at their upper edges adapting them to be folded upwardly, a cut-out in the closing flap, said reenforcing tongue adapted to be folded upwardly prior to folding down of the flap, the locking tongue 10 adapted to be folded upwardly into said cut against the flap when the flap is folded down, the cut-out in the flap being of less width than that of the locking tongue.

15

GEORGE W. POPPE.
